UNITED STATES PATENT OFFICE.

RALPH P. HARLAN, OF CHICAGO, ILLINOIS.

TOP.

1,321,035.

Specification of Letters Patent.

Patented Nov. 4, 1919.

Application filed January 17, 1919. Serial No. 271,597.

To all whom it may concern:

Be it known that I, RALPH P. HARLAN, a citizen of the United States, residing at Chicago, in the county of Cook and State of Illinois, have invented a certain new and useful Improvement in Tops, of which the following is a full, clear, concise, and exact description, reference being had to the accompanying drawings, forming a part of this

10 specification.

My invention relates to tops, an object being to provide an improved and simplified construction, one of the features residing in a novel spindle construction. Another feature of my invention lies in the provision of a comparatively heavy flat disk body covered with thin sheet metal in intimate contact therewith and suitably secured to the disk, preferably by drawing the facing over 15 the peripheral edge of the disk.

I also preferably provide a roughened surface on the upper or thin facing so as to more effectively propel various disks which may be placed thereon, these disks being 20 color plates which produce various color effects while the top is spinning. This roughened surface on the top is preferably in the nature of circular rows of projections of predetermined numbers so as to form a musical 25 scale.

For a better understanding of my invention reference is to be had to the accompanying drawings, in which—

Figure 1 is a plan view of the preferred 30 form of my invention;

Fig. 2 is a transverse section through Fig. 1;

Fig. 3 shows the top carrying a plain paper disk adapted to be colored while spinning; and

Fig. 4 is a modified form of spindle construction in which the spinning shank is integral with the body portion.

Referring now more in detail to the construction employed, I provide a flat, comparatively heavy, sheet metal disk 5 covered by a comparatively thin sheet metal facing 6 drawn over the peripheral edge of the disk and clenched thereon. The facing 6 is preferably made of sheet metal enameled or painted before forming. I preferably provide a roughened surface on the facing 6 so as to more readily propel colored disks 7 which may be placed thereon, retarding 50 means in the form of a winged device 8 being placed upon the top of the disks 7 so as

to retard their speed of rotation. The device 8 has bent up portions 8^a which retard the movement thereof, this device 8 being slightly creased at 8^b and 8^c, so that it may 60 be turned up from either edge depending upon whether the top is to be spun by a right or left handed person. Thus it will be seen that as the top is spinning, the top itself tends to rotate the disks 7 in one direction 65 and the wing device 8 tends to retard their advance so that their relative position is constantly changing, thereby producing a varied colored effect.

Now this thin metal facing 6 in being 70 roughened for the purpose of more effectively propelling the colored disks, preferably contains a plurality of circular rows of projections displaced from the metal itself and of predetermined numbers, so as to form 75 a musical scale. Thus, when the top is spinning without any of the disks thereon, by placing the tip of a small paper cone 9 against the various rows of projections, simple tunes may be played. This broadly is 80 not new, my invention being directed more to improvements of construction.

I also provide a spinning shank 10 having one end turned down so as to provide an annular shoulder, this end extending through 85 the disk 5 and facing 6 and being staked thereto so as to be rigidly held in place. A spinning string 11 is wound around the shank 10 for spinning the top. The spindle is preferably in the form of a rod 12 having 90 a swaged annular flange 12^a which is of course integral with the spindle proper and adapted to abut the upper end of the shank 10. The spindle extends down through the spindle bearing in the shank 10 and in order 95 to retain the spindle in position, I preferably slip a washer 13 over the lower end and hold it in place by swaging a plurality of ears 12^b around the peripheral surface of the spindle. The spindle is thus effectively retained in 100 position, the upper integral annular flange 12^a also acting as a rest for the removable handle 14. In spinning the top there is usually considerable strain or pressure placed upon the flange 12^a and I have found great 105 difficulty in maintaining the spindle in proper working order when separate elements 12^a are fastened to the spindle. In my improved construction, however, the flange 12^a is swaged integrally with the spindle 12 110 and is always maintained in proper position. Thus it will be seen that the spindle is main-

tained easily rotatable within the shank due to the swaged integral portions 12^a and 12^b at opposite ends of the shank.

In Fig. 3, I have shown my improved top 5 carrying a plain paper disk 15 adapted to be colored while the top is spinning, by means of a paint brush 16 applied thereto. Disks, as 15, may be placed upon the top and removed while spinning, being effectively held in position upon the top due to the projections upon the facing 6.

In Fig. 4, I have shown a modified form 15 of shank and spindle construction in which the shank 10^a is integral with the body portion 5, the shank in this case being drilled to provide a suitable spindle bearing.

By means of my improved construction I provide a cheap simple top which when once assembled is maintained in good working 20 order and because of its flat shape and novel spindle construction spins for comparatively long periods.

Although I have shown several forms of my invention, it is to be understood that this 25 is only for the purpose of illustration, and it will be apparent that changes and modifications will readily occur to those skilled in the art, and therefore I do not desire to be limited to the exact structures shown and 30 described, but aim to cover all that which comes within the spirit and scope of the appended claims.

I claim—

1. A top comprising a body portion, a 35 spinning shank having a rotatable spindle bearing therein, a spindle having a swaged annular flange abutting the upper end of the shank, and means at the other end of the spindle for retaining it in the shank.
2. A top comprising a body portion, a 40 spinning shank having a rotatable spindle bearing therein, a spindle having a swaged annular flange abutting the upper end of the shank, and swaged retaining means at 45 the other end of the spindle.

Copies of this patent may be obtained for five cents each, by addressing the "Commissioner of Patents, Washington, D. C."

3. A top comprising a body portion, a spinning shank having a rotatable spindle bearing therein, and a spindle having integral retaining means at each end of the shank.

4. A top comprising a heavy flat sheet metal disk, a comparatively thin sheet metal facing in intimate contact with the disk and drawn over the peripheral edge thereof, a shouldered spinning shank extending 50 through the disk and facing and staked thereto, and a rotatable spindle extending through the shank.

5. A top comprising a heavy flat sheet metal disk, a comparatively thin sheet metal 60 facing in intimate contact with the disk and drawn over the peripheral edge thereof, a shouldered spinning shank extending through the disk and facing and staked thereto, and a rotatable spindle extending 65 through the shank having integral retaining means at each end of the shank.

6. A top comprising a heavy flat sheet metal disk, a comparatively thin sheet metal facing in intimate contact with the disk, 70 said facing having circular rows of projections forming a musical scale, and means for holding the disk and facing together.

7. A top comprising a heavy flat sheet metal disk, a comparatively thin sheet metal 75 facing in intimate contact with the disk and drawn over the peripheral edge thereof, said facing having circular rows of projections forming a musical scale.

8. A top comprising a heavy flat sheet metal disk, a comparatively thin sheet metal facing in intimate contact with the disk and drawn over the peripheral edge thereof, said 80 facing having circular rows of projections forming a musical scale, and a spinning shank and spindle for the disk and facing.

In witness whereof I hereunto subscribe my name this 7th day of January, A. D. 1919.

RALPH P. HARLAN.
